[57] CLAIM

The ornamental design for height measuring device, as shown and described.

DESCRIPTION

FIG. 1 is a front elevational view of a height measuring device showing my new design;

FIG. 2 is a left side elevational view thereof;

FIG. 3 is a top plan view thereof;

FIG. 4 is a partial top-left perspective view of FIG. 1 on an enlarged scale; and

FIG. 5 is a top and right perspective view of the movable measure bar on an enlarged scale, the base/support unit being omitted for ease of illustration.

FIG. 1

FIG. 2

FIG. 3

FIG. 4

FIG. 5
